UNITED STATES PATENT OFFICE.

ROMOLO LIBANI, OF GENOA, ITALY.

APPARATUS FOR LAUNCHING LIFEBOATS.

Application filed June 20, 1925, Serial No. 38,503, and in Italy September 25, 1924.

This invention relates to apparatus for use in launching lifeboats from ships.

The apparatus preferably comprises:

(a) A lattice structure in the form of a cradle in which the lifeboat is supported;

(b) Two standards or supports of a special type, which take the place of the usual davits;

(c) An hydraulic brake connected to the drum around which is coiled the cables for suspending the boat-cradle system, the said brake being mounted either on the ship or in the cradle.

The hydraulic brake in this apparatus is preferable to the friction brake because it is very reliable in its operation, and also because during the lowering of the boat-cradle system the lowering speed can be easily regulated or can be kept uniform from the beginning until the boat has reached the sea, thus avoiding the use of devices for controlling the braking.

The annexed drawings diagrammatically show some embodiments of the present invention, and particularly:

Fig. 1 and Fig. 2 show respectively an end and a side view of one form of the present device, with the drum and the brake arranged lengthwise on the deck of the ship;

Fig. 3 is a plan view of the device, with the brake and the drum arranged crosswise on the deck of the ship;

Fig. 4 is a plan view of the device, but with the brake and drum arranged longitudinally in the cradle;

Fig. 5 is a plan view with the brake arranged transversely of the cradle;

Fig. 6 is a plan view of part of the device, as shown at Figs. 1 and 2.

The usual davits which hold the boats are substituted by two vertical standards A and B, constructed with a trellis structure of cast steel work, mounted transversely on the deck of the ship and having outer sections C hinged or otherwise rotatably connected thereto by suitable pivots.

The upper edges of parts A, B, C are inclined in the outbound direction and are provided with rails upon which engage two rollers r, r'; these rails carrying the cradle R.

Each of the supporting cables S is fixed at one end of the cradle and is passed around the pulleys b and a to the winding drum T as shown in Figure 3, where the drum and brake are arranged crosswise on the ship.

The disposition of the ropes and pulleys

in another embodiment in which the brake is arranged lengthwise of the ship, has been clearly shown in Figs. 2 and 6.

Ordinarily the cradle with the boat there-
in remains in its upper position, which is indicated in full lines in Fig. 1. The rollers r, r' are mounted on guide rails and the whole is held by the cables S, S. The hinged sections C of the standards are ordi-
narily in the position as shown in Fig. 1 and in the dotted lines at Fig. 3, viz, as a continuation of the fixed parts A, B; but when projection over the ship's side is objectionable the parts C can be rotated through 90° 70 towards the deck of the ship, as shown in full lines at Fig. 3.

In order to lower the boat and boat-cradle system it is sufficient to release the brake by opening the cock V.

By doing this, the rollers r, r' are per-
mitted to roll upon the rails by action of the
weight of the boat, as shown by dotted lines
in Fig. 1. When the rollers are at the lower
ends of the rails, the cables S engage in the
end pulleys c, c, and the cradle descends per-
pendicularly until the ropes are completely
uncoiled, and thus the cradle descends un-
der the water, while the boat remains freely
afloat.

Alternatively the brake with the drum
may be arranged on the cradle. Fig. 4 il-
lustrates this arrangement, with the drum
and the brake arranged on the same axis
lengthwise of the cradle, but of course the
drum with the brake could be arranged
crosswise as shown in Figure 5. In the lat-
ter case the axes of the brake and of the
drum are parallel and coupling is effected by
means of two pinions O.

The hydraulic brake, of which in the draw-
ings two embodiments are shown in section,
comprises a cylindric body D in which a
piston M is adapted to slide.

As the piston is rendered fluid tight, it 100
divides the said cylinder into two chambers,
which can communicate with each other only
by means of a conduit p provided with a
cock V.

A screw threaded shaft N is coupled either 105
directly or through gears O to the drum T
around which are coiled the cables S from
which the cradle is suspended. The said
shaft N can be screwed into the piston, so
that by rotation of the threaded axle, the 110
piston is caused to slide longitudinally, as the
rotation of the piston is prevented by suit-

able wings with which it is provided, and which slide in grooves formed in the inner surface of the cylinder.

By suitably opening the cock V, the passage of the liquid from one chamber to the other can be regulated, and thus the displacement of the piston and the lowering speed of the cradle containing the boat are suitably regulated.

- 10 When the brake is arranged on the cradle; the cock V is operated by an operator in the boat. When the brake is arranged on the ship the operation is effected from aboard the ship, or if preferred, also from 15 aboard the boat, for example, by means of a flexible tube, as shown at Figs. 4 and 5.

I claim:—

1. A device of the class described, comprising a pair of supports positioned in 20 spaced relation, a folding section hinged to each of said supports for horizontal rotation, inclined rails supported by said supports and by said folding sections, a boat-carrying cradle, rollers mounted on said 25 cradle and adapted to roll on said rails, cables secured to said cradle, a winding drum for said cables, and a pair of sheaves mounted on the outer ends of the folding sections in such position that the downward 30 movement of the cradle will carry the cables over the sheaves and into engagement therewith.

2. Apparatus for launching lifeboats comprising, a boat-carrying cradle, rollers on 35 the ends of the cradle, supports mounted on the ship, movable sections hinged to said supports and adapted to project over the ship's side, inclined rails extending along the upper edges of said supports and of said 40 movable sections and adapted to receive said rollers, suspending cables, a drum mounted in the said cradle and carrying the cable, a control and brake device, rotary means for transmitting motion from the drum to

the said device, and sheaves on said movable sections for receiving the said cables when the boat is being lowered.

3. Apparatus for launching lifeboats comprising, a boat-carrying cradle, rollers on 50 the ends of the cradle, supports mounted on the ship, movable sections hinged to said supports and adapted to project over the ship's side, inclined rails extending along the upper edges of said supports and of said 55 hinged sections and serving as guides for the said rollers, suspending cables, a drum for the cables, sheaves on the hinged sections for receiving the said cables when the boat is being lowered, and a control and brake device comprising a cylinder, a piston dividing the cylinder into two chambers, screw mechanism for operating the piston from the said drum and means for controlling the 60 passage of fluid from one cylinder chamber to the other to control the longitudinal movement of the piston and the rotary movement 65 of the drum.

4. Apparatus for launching lifeboats comprising, a boat-carrying cradle, rollers on 70 the ends of the cradle, supports mounted on the ship, movable sections hinged to said supports and adapted to project over the ship's side, inclined rails extending along the upper edges of said supports and serving as guides for the said rollers, suspending 75 cables, a drum for the cables, sheaves on said movable sections for receiving the said cables when the boat is being lowered, and a control and brake device comprising a cylinder, a piston mechanically connected with 80 the drum and dividing the cylinder into two chambers, a pipe connecting one cylinder chamber with the other, and a valve controlling the passage of fluid through such pipe to control and regulate movement of 85 the piston and of the cable drum.

In testimony whereof I affix my signature.
ROMOLO LIBANI.
